US0D1033774S

(12) **United States Design Patent** (10) Patent No.: **US D1,033,774 S**
 Liu et al. (45) Date of Patent: ** Jul. 2, 2024

(54) **CLEANER**

(71) Applicants: **JIANGSU MIDEA CLEANING APPLIANCES CO., LTD.**, Suzhou (CN); **MIDEA GROUP CO., LTD.**, Foshan (CN)

(72) Inventors: **Gang Liu**, Suzhou (CN); **Supphachai Lertwitthayaphon**, Suzhou (CN); **Jin Wang**, Suzhou (CN); **Chang Liu**, Suzhou (CN); **Pei Cao**, Suzhou (CN)

(73) Assignees: **Jiangsu Midea Cleaning Appliances Co., Ltd.**, Suzhou (CN); **Midea Group Co., Ltd.**, Foshan (CN)

(**) Term: **15 Years**

(21) Appl. No.: **29/783,872**

(22) Filed: **May 17, 2021**

(30) **Foreign Application Priority Data**

Dec. 7, 2020 (CN) 202030750657.6

(51) LOC (14) Cl. **15-05**

(52) U.S. Cl.

USPC **D32/22**

(57) **CLAIM**

The ornamental design for a cleaner, as shown and described.

DESCRIPTION

FIG. 1 is a front elevation view of a cleaner, showing our new design;

FIG. 2 is a back elevation view thereof;

FIG. 3 is a left side view thereof;

FIG. 4 is a right side view thereof;

FIG. 5 is an enlarged top plan view thereof;

FIG. 6 is an enlarged bottom plan view thereof; and,

FIG. 7 is a perspective view thereof.

The broken lines shown in the figures depict portions of the cleaner that form no part of the claimed design.

1 Claim, 7 Drawing Sheets
